WHEEL CHAIR

Mike Menuto, Erie, Pa., assignor to Erie City Manufacturing Company, Erie, Pa., a corporation of Pennsylvania

Filed Dec. 13, 1968, Ser. No. 14,951

Term of patent 14 years

Int. Cl. D6—01

U.S. Cl. D15—1

The figure is a perspective view of a wheel chair showing my design with one of the arm rests thereof in its retracted position.

The essential features of my design are the full line portions which are characterized by the two trapezoidal arm rests having hollow bottom bar portions adapted to receive the horizontal frame bar members, whereby to convey the appearance of a single bar when in contracted position, all as shown.

I claim:

The ornamental design for a wheel chair, as shown and described.
